ARCHITECTURAL GRILLE

Louis Blum, Pittsburgh, Pa., assignor to Blumcraft of Pittsburgh, Pittsburgh, Pa., a firm

Application November 19, 1958, Serial No. 53,443

Term of patent 14 years

(Cl. D54—2)

Fig. 1 is a plan view of an architectural grille embodying my new design;

Fig. 2 is a cross sectional view along the line II—II of Fig. 1; and

Fig. 3 is an enlarged front view of one of the grille elements.

The dominant features of my invention reside in those portions shown in solid lines.

I claim:

The ornamental design for an architectural grille, as shown and described.
